[57] CLAIM

The ornamental design for an enclosure for a studio, as shown and described.

DESCRIPTION

FIG. 1 is a perspective view of an enclosure for a studio showing my new design, the broken line showing of the studio is for illustrative purposes only and forms no part of the claimed design;

FIG. 2 is a top plan view thereof;

FIG. 3 is a side elevational view thereof taken from direction 3 in FIG. 2; and

FIG. 4 is a side elevational view thereof taken from direction 4 in FIG. 2.
